(57) **CLAIM**

The ornamental design for a head for ink cartridge for computer printers, as shown and described.

DESCRIPTION

FIG. 1: Front view of a first embodiment of the head for ink cartridge for computer printers;

FIG. 2: Back view thereof;

FIG. 3: Top view thereof;

FIG. 4: Bottom view thereof;

FIG. 5: Left view thereof;

FIG. 6: Right view thereof;

FIG. 7: Perspective view thereof;

FIG. 8: Perspective view thereof;

FIG. 9: Perspective view thereof;

FIG. 10: Perspective view thereof;

FIG. 11: Front view of a second embodiment of the head for ink cartridge for computer printers;

FIG. 12: Back view thereof;

FIG. 13: Top view thereof;

FIG. 14: Bottom view thereof;

FIG. 15: Left view thereof;

FIG. 16: Right view thereof;

FIG. 17: Perspective view thereof;

FIG. 18: Perspective view thereof;

FIG. 19: Perspective view thereof; and,

FIG. 20: Perspective view thereof.

1 Claim, 20 Drawing Sheets
